UNITED STATES PATENT OFFICE.

IRA REYNOLDS, OF REDWOOD FALLS, MINNESOTA.

DESIGN FOR A RACK.

6,476.

Specification for Design. Patented Oct. 26, 1920.

Application filed July 12, 1920. Serial No. 395,778. Term of patent 14 years.

To all whom it may concern:

Be it known that I, IRA REYNOLDS, a citizen of the United States, residing at Redwood Falls, in the county of Redwood and State of Minnesota, have invented a new original, and ornamental Design for a Rack, of which the following is a specification, reference being had to the accompanying drawings, forming a part thereof.

The figure is a perspective view of the rack, showing my new design.

I claim:

The ornamental design for a rack, as shown.

IRA REYNOLDS.
